George Sitter,

UNITED STATES PATENT OFFICE

GEORGE LITTLE, OF RUTHERFORD PARK, NEW JERSEY.

IMPROVEMENT IN AUTOMATIC TELEGRAPH APPARATUS.

Specification forming part of Letters Patent No. 96,333, dated November 2, 1869.

CASE B.

To all whom it may concern:

Be it known that I, GEORGE LITTLE, of Rutherford Park, in the county of Bergen and State of New Jersey, have invented and made a certain new and useful Improvement in Automatic Telegraph Instruments; and I do hereby declare the following to be a full, clear, and exact description of the same, reference being had to the annexed drawing, making part of this specification, wherein—

Figure 1 is an elevation of the said apparatus or instrument. Fig. 2 is a plan of the same below the line xx , Fig. 1. Fig. 3 is a vertical section of the motor and other portions of the instrument, and Fig. 4 is an inverted plan of a portion of the motor employed by me.

Similar marks of reference denote the same parts.

In the drawing, I have shown my automatic telegraph instrument as actuated by an electro-magnetic motor; but as the same forms a separate matter of invention, I will only describe it sufficiently to show the connection of the two when introduced in one instrument.

My present invention relates to a means for actuating a strip of paper, and transmitting telegraph pulsations to be employed in giving marks in the same character of instrument when used for receiving the message.

In the telegraph instruments heretofore employed for transmitting by perforated paper, a brush of fine steel wire has been used to penetrate the perforations and close the circuit through the roller.

This brush is apt to become injured by the electricity when in use, and the same is liable to wear or injure the paper. To avoid this I make use of a roller, with an edge of platina or other incorrodible metal, and I apply tension to the strip of paper by means of a brush, beneath which the strip of paper passes.

In the drawing, a represents the frame; b and c the magnets; d , the spindle; e , the armatures, and f the governor of an electro-magnetic motor, that is applied to give rotation to the shaft w' , by means of a worm-pinion, v , and gear w , or other convenient mechanism. This motor being a separate

matter of invention does not require further description.

Upon the shaft w' is the roller b' , and the shaft w' is sustained by the cross-bar c' , between the columus d^1 e' . The column d^1 carries a frame, d^2 , and roller f' that is of non-conducting material, and can be swung into contact with the strip of paper that passes around the roller b' and between the flanges thereof, so that said paper is fed along by the action of the rollers b' and f' , and g' is a spring, formed and applied so as to act to hold the roller f' to the roller b' , or keep it in position when moved back by the handle h' , to allow for introducing or removing the strip of paper.

The strip of paper passes in through a trough, l , over which is an inclined brush, 20, made of bristles set in a metal head, which metal head is in a slot in a projecting stud, 21, and a screw, 22, holds the said brush in position when placed, so that it gives the desired pressure upon the paper for detaining the same sufficiently to cause said paper to set smoothly against the surface of the metal roller b' .

The end of the column e' projects beyond the cross-bar c' , and carries the arm n' for the non-corrodible stylus, there being a cylinder of hard rubber, or other non-conducting material, intervening between the end of the column and the cylindrical base of the arm, so as to insulate the arm n' .

The connection between the cylindrical base of the arm n' of the stylus and the binding-screw p^1 is effected by the spring o' , and the binding-screw p^1 is insulated from the column e' , so that the electrical circuit passes from the binding-screw p^1 to the arm n' and stylus, thence to the roller b' , and by the bar c' and column d to the binding-screw p^2 of the line or battery wire. The arm n' , carrying the stylus, is made with a joint, r' , so that it can be turned back, and the spring t presses the stylus to the paper.

I make use of a disk-formed stylus, with a platina or other non-corrosive metal edge; and said stylus is held by jaws that slip into the end of the arm n' , as shown more particularly in detached views, Sheet 3.

By the use of a disk-stylus injury to the pa-

per is prevented, the mechanism runs with less power, and, instead of the stylus wearing out rapidly by contact with the paper, the disk remains in constant working condition.

What I claim, and desire to secure by Letters Patent, is—

1. The adjustable brush 20, in combination with the roller b' and stylus, substantially as and for the purposes set forth.

2. The stylus formed of a disk, with a pla-

tina or non-corrosive edge, in combination with the arm w' and roller b' , as and for the purposes set forth.

In witness whereof I have hereunto set my signature this 28th day of July, A. D. 1869.

GEORGE LITTLE.
